US00D859460S

(12) United States Design Patent (10) Patent No.: US D859,460 S
Kaminer et al. (45) Date of Patent: * Sep. 10, 2019

(54) DISPLAY SCREEN OR PORTION THEREOF WITH GRAPHICAL USER INTERFACE

(71) Applicant: Delos Living LLC, New York, NY (US)

(72) Inventors: Barrett Brod Kaminer, New York, NY (US); Max Andrew Pollinger, New York, NY (US); Tarynne Blake Lopez, Cranford, NJ (US); dingane Richard St Arromand, New York, NY (US); Shivaun Ryan, South Yarra (AU); Chris David Hall, Narre Warren South (AU); Shaun Benson Stewart, New York, NY (US)

(73) Assignee: Delos Living LLC, New York, NY (US)

() Term: 15 Years

(21) Appl. No.: 29/628,142

(22) Filed: Dec. 1, 2017

(51) LOC (12) Cl. 14-04

(52) U.S. Cl.

USPC D14/488; D14/489

(57)

CLAIM

The ornamental design for a display screen or portion thereof with graphical user interface, as shown and described.

DESCRIPTION

The FIGURE is a front view of a display screen or portion thereof with graphical user interface.

The broken line showing of the words "Favorites" and "Climate," the icons above those words, and the remainder of the display screen is for environmental purposes only and forms no part of the claimed design.

1 Claim, 1 Drawing Sheet
